UNITED STATES PATENT OFFICE.

JAMES L. HASTINGS, OF NEW ORLEANS, LOUISIANA, ASSIGNOR, BY MESNE ASSIGNMENT, TO BERNHARD WELKER, CONRAD REITER, BERNHARD KRUGH, HUGH LAFFERTY, AND WILLIAM B. HOLLIS, IN TRUST FOR HASTINGS COTTON PICKER MANUFACTURING COMPANY.

COTTON-PICKER.

SPECIFICATION forming part of Letters Patent No. 243,131, dated June 21, 1881.

Application filed May 28, 1878.

To all whom it may concern:

Be it known that I, JAMES LANCE HASTINGS, of New Orleans, in the parish of Orleans and State of Louisiana, have invented 5 a new and useful Improvement in Machines for Picking Cotton, which improvement is fully set forth in the following specification, reference being had to the accompanying drawings.

10 My invention relates to a machine for picking cotton from the plant, to be propelled through the field of plants by horse or other motive power; and it consists in the general form and construction of the machine, and in 15 the construction and arrangement of parts of the same, as hereinafter described, and specifically pointed out in the claims.

20 In the drawings, Figure 1 is an elevation, showing the picking side of a machine embodying my invention. Fig. 2 is a plan view. Fig. 3 is a view of the opposite side from that of Fig. 1. Fig. 4 is an elevation of the forward end. Fig. 5 is an elevation of the rear end. Fig. 6 is a vertical section taken on line 1 1 of 25 Fig. 2. Fig. 7 is a side and Fig. 8 a plan view of the shield or guide-plate. Fig. 9 is a vertical section, taken on line 2 2 in Fig. 2, of the extension-arm and its guide. Fig. 10 is a face view of the external shield or guard. Figs. 30 11 and 12 are views of two sides, and Fig. 13 an end view of a pair of pickers drawn on a larger scale.

35 The frame of the machine consists of the longitudinal pieces A, cross-pieces B, uprights C, bottom board or platform, D, top board or covering, E, having suitable braces, as shown. The rear of the machine rests on the one broad-faced wheel F. The longitudinal piece G is connected to and placed lower than one of the 40 pieces A, of which it serves as a part or extension to let down one side and incline the covered portion of the machine. The curved pieces H and cross-piece B' allow the forward part of the machine to rest on a wheel, I, which may swivel on a pivot at a for directing 45 the machine. The seat for a driver is shown at J, and portions of shafts for one horse at c'. It will be seen that the bottom D is inclined considerably, and that the body or cov-

ered portion is tipped. By this means the 50 picking side of the machine is brought to conform to the pyramidal shape of the plants and the lower edge brought nearer the ground, and the bottom on the opposite side of the machine may extend over a portion of the adjacent row 55 of plants. The top E is parallel with the bottom D. Two plates or disks parallel to each other are centrally pivoted, the one, K, to revolve on the upper side of the bottom D, and the other, L, on the under side of the 60 top E. These disks do not have their axes in the same line, owing to the inclination of the top and bottom to the supports C. These disks revolve about their axes at the same speed, being driven by the pinions b and c engaging with the teeth shown thereon, so that the sides toward the plants being picked shall move in an opposite direction from, but the same speed as, the forward movement of the 65 machine.

70 Four picker-rods M are here shown, although any suitable number may be used. These rods are pivoted at their lower ends to the disk K, and at their upper ends to the disk L, being pivoted rather than fastened rigidly to the 75 disks to preserve the same inclination as they are carried by the disks. Each picker-rod is shaped or bent to form in appearance a succession of cranks.

70 The pickers N consist each one of a core, d, 80 on the outside of which are fastened the bent wires or teeth, similar to those of "card-clothing." I prefer to use card-clothing, which, being in strips, I wind spirally about a cylindrical core, d, and thus cause the wires or teeth 85 to hook in the direction in which the picker is revolved in the plant, and also slightly toward the inner end. Each picker is rounded at its outer end or point to prevent injury to the plant, and is centrally and longitudinally journaled, having at its inner end a gear or fluted roller, e. The pickers are best arranged in pairs, two being connected by a bar, f, which is pivoted at each end to one of the rods or shafts g, on which the pickers revolve, and 90 which has a bearing or box, h, for the picker-rod. Only a few pickers are shown in the drawings; but any desired number may be used,

arranged on the picker-rods, as shown, from the bottom to the top of the machine.

Horizontal bars O, only two of which are shown in the drawings, are secured to the picking side of the machine, as many as are required, and so as to leave spaces between them. On the upper edge of each of the bars O, for the distance required, are the teeth i.

As the disks K and L revolve the picker-rods M will be carried around, and will bring the pickers N to the picking side of the machine and thrust them endwise through the spaces between the bars O into the plants. As the pickers are carried along the bars O the gears or fluted rollers e will engage with the teeth on the bars, and the pickers will be revolved and will wind upon themselves the cotton with which they come in contact, and which is caught by the bent wires or teeth thereon. Flanges j are on the shanks of the shafts g, which, bearing against the inner sides of the bars O, will cause each one of a pair of pickers to project at right angles to the side of the machine. Owing to the crank form of the picker-rods M, any two adjacent pairs of pickers will alternate in entering and being withdrawn from the plants, and on account of the speed and direction of motion of the disks K and L the pickers will enter and be withdrawn endwise, having no sidewise movement with reference to the plants. As the pickers are withdrawn from the plants they enter the machine through the spaces between the bars O and are carried near the cleaning-belts P. There is a shield or curved guide-plate, Q, to direct the pickers as they are carried around in the machine, there being a projection, k, on the shank of the shaft g of each picker to bear against the guide-plate. Each projection k will also come in contact with one of the projections or ribs l on the inner side of the guide-plate, to throw each pair of pickers around, so that they will be carried against the cleaning-belts P and be made to enter and project from the machine in a line at right angles to its picking side.

There are two cleaning-belts P, one at the rear and the other at the forward portion of the covered part of the machine. Each of these belts passes about two pulleys, one, R, at the top and the other, S, at the bottom of the machine, and is so driven as to cause the inner portion to move upward. Wires or teeth are fixed in these belts to project from the outer surface and to curve or hook in the direction of motion. One of each pair of pickers will be brought in contact with one of the cleaning-belts, and the other picker with the other cleaning-belt. The motion of the cleaning-belts will cause the picker with which it is brought in contact to revolve, and, removing the cotton therefrom, will carry it upward and over against one of the two brush-wheels T. These brush-wheels are revolved rapidly in a direction to clear the cotton from the belts, and by aid of the casings U, only one of which is shown in

the drawings, will collect and deliver the cotton into bags or other suitable receptacles hung on the spouts formed with the casings U, or otherwise attached to the machine.

I prefer to drive the moving parts of the machine as follows: On the shaft of the main supporting and driving wheel F is a chain-pulley, V, which may be thrown in or out of connection with the wheel F by a clutch, m, 70 operated by a rod, n, and hand-lever n'. About the pulley V runs a chain, W, which also passes about a pulley, o. On the same shaft with the pulley o is a pulley, o', and the pinion b to revolve with it. A chain passes about the pulley o' and a pulley, p. On the same shaft with the pulley p is a pulley, p', and the pinion c to revolve with it. A chain passes about the pulley p', and also about a pulley, q, having on the same shaft, to run with it, a gear, r. 80 The chain W runs under and gives motion to a pulley, s, having on the same shaft, to run with it, a pulley, s'. A chain runs from the pulley s' to a pulley, t, having on the same shaft, to run with it, a gear, u. Thus the cleaning-belts are driven, one of the pulleys R being on the same shaft with the pulley q, to run with it, and the other being on the shaft with the pulley t, to run with it. The gears r and u engage with gears on the same shafts with the 90 brush-wheels T, and thus the latter are driven.

A third wheel, X, is employed for the further support of the machine, which wheel runs on the ground at the side of the row of plants opposite from that being picked. This wheel 100 is held by an extension-arm, Y, which is curved in the proper form to pass over the plants and be held at the top of the machine, where it passes through and may slide in a box, v, and be held there by a set-screw or similar device. 105 The box v is pivoted to swing in a vertical plane to a stand, v', which is pivoted to top of machine to turn horizontally. A brace and guide, w, is set against the arm Y, and is fastened and made adjustable on the top of the 110 machine. The arm Y also passes through a slot in a vertical guide, x, which is fastened, braced, and made adjustable at the top of the machine, as shown. In the guide x are springs 115 y, which press one against the top and the other against the bottom side of the arm Y. By means of these springs the movement of the machine is eased, a rocking motion being allowed to the machine to conform to the inequalities of the ground.

A shield or guard-plate, Z, (shown only in Figs. 6 and 10), may be fastened on the face of the picking side of the machine, having slots corresponding to the spaces between the bars O, to further protect the plants from injury 125 and lessen the friction of the plants against the machine.

The machine shown is to pick on one side of a row of plants; and this form seems most desirable, as the machine may be drawn and the 130 machinery operated by the power of one horse; but, as will readily be seen, a double machine

may be constructed to operate in a similar manner to pick on the two adjacent sides of two rows of plants. My machine, being adapted to picking from the rows of plants, and being

5 conformable to the pyramidal form of the plants, both to reach the plants being picked and to clear and pass the row on the other side of the machine, will not require any change from the present mode of the cultivation of
10 cotton.

By preventing any sidewise movement of the pickers in the plants the unopened bolls or other portions of the plants will not be injured. On account of the endwise and downward-inclined thrust of the pickers into the plants all 15 of the cotton will be reached; and on account of their revolving motion while in the plants and the hooking of the teeth, as above stated, the greatest portion possible of the cotton will 20 be gathered. The pickers, on being withdrawn into the machine, pass through the slots in the outer shield or guard and between the bars O, which will clear the cotton of sticks and other coarse foreign matter.

25 The inclining of the sides and bottom of the machine and the use of the two wheels F and I, together with the third wheel on the other side of the row of plants, adapt the machine to travel in the narrowest space between the
30 rows.

As the pickers are made removable from the picker-rods, any required number may be used.

The machine is of proper height to pick from bottom to top of the plants; but certain pickings will require the pickers for only part of the height of the machine. The alternating motion of the pickers by the crank form of the picker-rods will contribute to cause the pickers to reach the cotton through the whole side
40 of the plants operated upon.

I claim as my invention—

1. A cotton-harvester having inclined bottom and sides, the main body being supported on wheels, and further braced and supported by an extension-arm with wheel, whereby the machine is adapted to bestride a row of plants and pass over the lower branches of the adjacent row, substantially as and for the purpose hereinbefore set forth.

50 2. The pickers N, in combination with the inclined picker-rods M, whereby said pickers enter the plants and are withdrawn, substantially as hereinbefore specified.

3. The pickers N, in combination with the inclined picker-rods M, each of the latter being 55 provided with several bends or cranks, substantially as hereinbefore set forth.

4. The pickers N, arranged in pairs, and in combination with the cross-bars f, each having a bearing or box, h, for a picker-rod, substantially as hereinbefore described.

5. A picker adapted to pick cotton from the plant, formed of a core, d, having teeth thereon looking in the direction of the revolution of the picker while in the plant, and having a 65 point smooth—that is, free from teeth—substantially as hereinbefore described.

6. The pickers N, having the gears or fluted rollers e, in combination with the racks and teeth i, whereby said pickers are revolved 70 while moving along and with reference to the body of the machine, substantially as hereinbefore specified.

7. The combination of the disks K and L and picker-rods M, substantially as hereinbefore 75 described.

8. The cleaning-belts P, constructed and arranged substantially as specified, in combination with the pickers N, arranged in pairs and brought in contact with them, as hereinbefore 80 set forth.

9. The combination of the pickers N, picker-rods M, disks K and L, and shield or guide-plate Q, substantially as hereinbefore described.

10. The pickers N, moved substantially as set forth, and having the projections k, in combination with the shield or guide-plate Q, having the projections or ribs l, substantially as hereinbefore specified.

11. The combination of the brush-wheels T, cleaning-belts P, and pickers N, arranged in pairs, substantially as and for the purpose hereinbefore set forth.

12. In a cotton-harvester having the body 95 thereof inclined, the combination of wheel X, extension-arm Y, and box v, pivoted substantially as hereinbefore described.

13. In a cotton-harvester, the combination of wheel X, extension-arm Y, guide x, and 100 springs y, substantially as and for the purpose hereinbefore specified.

JAMES LANCE HASTINGS.

Witnesses:
